CLAIM

The ornamental design for a computer port consolidation device, as shown and described.

DESCRIPTION

FIG. 1 is a front isometric view of a computer port consolidation device showing our new design;

FIG. 2 is a top plan view thereof;

FIG. 3 is a right side elevational view thereof;

FIG. 4 is a left side elevational view thereof;

FIG. 5 is a rear elevational view thereof; and,

FIG. 6 is a bottom plan view thereof.

The broken line showing throughout the views is included for the purpose of illustrating environmental structure only and forms no part of the claimed design.
